UNITED STATES PATENT OFFICE.

JAMES M. SHEPARD, OF BOSTON, MASSACHUSETTS.

VAPOR-BURNING FURNACE.

SPECIFICATION forming part of Letters Patent No. 349,906, dated September 28, 1886.

Application filed October 12, 1885. Serial No. 179,739. (No model.)

To all whom it may concern:

Be it known that I, JAMES M. SHEPARD, of Boston, in the county of Suffolk and State of Massachusetts, have invented certain new and useful Improvements in Vapor-Burning Furnaces, of which the following, taken in connection with the accompanying drawings, is a specification.

My invention relates to that class of furnaces in which oleaginous vapors are mixed with water vapor, (both produced by high temperature,) and, being mixed with air, are burned conjointly, the object being to so arrange the generators that the mixture is compounded near the point of ignition, thus avoiding all danger of chemical reaction of one of the elements upon the others before combustion. I accomplish this object by the mechanism shown in the accompanying drawings, 20 in which—

Figure 1 is a vertical section showing a part of a boiler with my improved apparatus located within its fire-box, also showing a part of the outside connections. Fig. 2 is a horizontal section taken on line X X of Fig. 1. Fig. 3 is a view showing a vertical section of the fire-box and an elevation of my generating apparatus. Fig. 4 is a vertical section of my apparatus, taken on line Y Y of Fig. 2. Fig. 30 5 is a detail showing in vertical section one of the mixing-pipes and a steam-jet device. Fig. 6 is an enlarged section showing the compound valve which admits and governs the flow of oil and water to my generator.

In the drawings, A, Figs. 1, 2, 3, and 4, represents the outer wall of the boiler, and A' the outer casing of the fire-box of a boiler. Within this casing A', I place my generating apparatus, which consists of a system of tubes arranged 40 to supply oil vapor, steam, and air for the purpose of producing jets of flame for evolving heat.

W', Figs. 1, 2, and 4, represents a retort placed within the fire-box and arranged to produce steam, it being supplied with water by the pipe w, Figs. 1, 2, 3, and 6, which connects it through the compound valve D, Figs. 1, 2, and 6, to the water-tank W, Figs. 1 and 2.

O', Figs. 2, 3, and 4, is a retort for vaporizing oil, and is supplied by the pipe o, Figs. 2, 3, and 6, which connects it through the com-

pound valve D, Figs. 1, 2, and 6, with the oil-tank O, Fig. 2. The water vapor or steam generated in the retort W' is delivered through the pipe W², Figs. 1, 2, and 3, to the annular 55 steam-delivery pipe W³, Figs. 1, 2, 3, and 4, thence to the cross steam-pipes W⁴, Figs. 1, 2, 3, and 4, to the jets, one of which, W⁵, is shown in Fig. 5. From the jet the steam passes into the pipe E, Fig. 5, and thence to the combustion-pipe E', Figs. 1, 3, and 4. The steam in passing from the jet-piece W⁵ to the pipe E is so arranged in connection with the said pipe E that it will throw air into the said pipe E, on the principle of the Giffard injector. Thus 65 two parts of my compound—namely, steam and air—are introduced through the pipe E.

The oleaginous vapor is produced within the retort O', Figs. 2, 3, and 4, said retort being supplied with oil from the tank O, Fig. 2, as 70 has been already stated. The vapor from this retort passes through the pipe O², Figs. 2 and 3, to the annular pipe O³; thence to the cross-pipes O⁴, Figs. 1, 2, 3, 4, and 5, and through the orifices O⁵, one of which is shown in Fig. 5, 75 to the combustion-tubes E'.

The number of the combustion-tubes and their precise location may be varied to suit the requirements of the device to which they are applied. Thus, if a great heat is required 80 within a small space, then these tubes E' should be placed closely together; but in case a moderate heat, distributed over a large area, is required, then the tubes may be placed much farther apart. T, Figs. 1, 2, 3, and 4, is a diaphragm placed near the top of the combustion-pipe E', as shown.

I will now describe my device for proportioning and regulating the supply of oil and water to the retorts. This device is shown in an enlarged section, Fig. 6, in which D D' represent the general frame or casing, and O⁶ and W⁶ represent, respectively, the oil and water chambers. The oil-chamber O⁶ receives its oil from the tank O, Fig. 2, through the pipe 95 o², Fig. 6, and the water-chamber W⁶ receives its supply from the water-tank W, Fig. 2, through the pipe w², Fig. 6.

D², Fig. 6, is a regulating-valve terminating in a point at o', which may be adjusted to the 100 orifice in the pipe o, Fig. 6, so as to allow more or less oil to flow from the chamber O⁶ to the

pipe o , and thence to the retort. d is another regulating-valve having its point w' , Fig. 6. This regulates the supply of water from the chamber W' to the pipe w , and thence to the water-retort W' . As the two regulating-valves D^2 and d are attached to an adjustable cross-head, D^5 , Fig. 6, by means of screws and finger-pieces $D^3 D^4$ and $d' d^2$, they may be regulated so that one may leave a larger orifice than the other. For instance, the flow of water at the point w' may be much larger than the flow of oil at the point o' , or, if desirable, vice versa, while the quantity to be supplied may be regulated by raising or lowering the cross-head D^5 by simply operating the screw D^6 by aid of the hand-wheel D^7 .

For convenience in kindling—that is, furnishing preliminarily the heat required to vaporize the oil and water—I connect with the oil-tank O , Fig. 2, a pipe, K , having branches $K^2 K^3$. These branches are perforated, K^2 passing under the oil-retort and K^3 under the water-retort, as shown in Fig. 2, K' being a valve for admitting oil to these pipes.

$L L'$ are valves, one of which is located between the water-tank W and the compound valve D and the other between the oil-tank O and the compound valve D . These are to be used when the apparatus is not working.

By the arrangement for mingling the compound which I burn, as shown in Fig. 5, I effectually prevent any communication of flame to the oil, from the fact that vapor of oil unmixed with oxygen will not burn, and there being no oxygen below the point M in the

pipe E' , Fig. 5, the flame cannot communicate with the oil-orifice O^5 . Therefore this arrangement insures great safety of the apparatus, as it is impossible for the flame to "snap" down below the point M in the pipe E' . 40

I am aware that oleaginous vapors, steam, and air have been previously united before burning, and I am also aware that pressure-regulators have been used for governing the flow of the said compounds, and therefore do 45 not broadly claim the use of the compound or of the regulator; but

I do claim as my invention, and desire to secure by Letters Patent—

1. In vapor-burning furnaces, the combination of the oil-vapor supply-pipe $O^4 O^5$ with the pipe E' , said pipe E' having near its ignition end an air and steam supply pipe, E , substantially as described, and for the purpose set forth. 50

2. The combination of the pipes $o o^2$ and $w w^2$ with the regulating-valves $D^2 d$ and their adjusting devices $D^3 D^4 d' d^2$, with the cross-head D^5 and adjusting-screw $D^6 D^7$, substantially as described, and for the purpose set 55 forth.

In testimony whereof I have signed my name to this specification, in the presence of two subscribing witnesses, on this 9th day of October, A. D. 1885.

JAMES M. SHEPARD.
